UNITED STATES PATENT OFFICE.

IRA E. STUMP, OF CANTON, OHIO, ASSIGNOR OF ONE-HALF TO JACOB M. SCHNEIDER, OF SAME PLACE.

LAND-ROLLER.

SPECIFICATION forming part of Letters Patent No. 552,794, dated January 7, 1896.

Application filed March 20, 1895. Serial No. 542,470. (No model.)

To all whom it may concern:

Be it known that I, IRA E. STUMP, a citizen of the United States, residing at Canton, in the county of Stark and State of Ohio, have 5 invented certain new and useful Improvements in Land-Rollers; and I do hereby declare that the following is a full, clear, and exact description of the same, reference being had to the annexed drawings, making a part 10 of this specification, and to the letters of reference marked thereon, in which—

Figure 1 is a perspective view of the roller. Fig. 2 is a detached view of one of the rollers. Fig. 3 is a view showing the end of one of the 15 rollers and illustrating a manner of securing the ends of the spiral pipes, also showing the spider removed. Fig. 4 is a vertical section of the front or forward roller. Fig. 5 is a detached view of one of the spiders.

20 The present invention has relation to land-rollers; and it consists in the different parts and combination of parts hereinafter described, and particularly pointed out in the claim.

25 Similar letters of reference indicate corresponding parts in all of the figures of the drawings.

In the accompanying drawings, A represents the end blocks or heads, which may be 30 substantially of the form shown, or they may be of any other desired form inasmuch as their only purpose is to support the roller shafts or bars, or, in other words, hold said bars in proper position with reference to the rollers, 35 and at the same time hold the connecting-bars. The roller shafts or bars B are formed of a length to correspond with the length of the roller proper, and are properly secured to the blocks or heads A by means of the heads 40 a or their equivalents.

Upon the shafts or bars B are mounted the rollers C and D, said rollers being located and arranged substantially as shown in Fig. 1. Upon the peripheries of the rollers C and D 45 are located the spiral or screw-like tubes b and c, which spiral tubes may be secured at their ends, as illustrated in Fig. 3, or they may be differently secured, as it is immaterial how or in what manner the ends are secured.

50 The rollers C are located in front of the roll-

ers D and the pitch of the spiral tubes is reversed upon each set of rollers—that is to say, if the pitch of the tubes b is such as to form a right-handed screw, the pitch of the tubes c should be such as to form a left-hand screw. 55

The object and purpose of forming the tubes b and c and locating them upon the peripheries of the rollers is to provide a better means for pulverizing the ground. The ends of each of the rollers C and D are provided with the 60 spiders E, said spiders being located substantially as illustrated in Fig. 2, and are for the purpose of providing suitable bearings for the rollers proper.

For the purpose of preventing the shafts or 65 bars B from bending, the center support F is provided, which center support is attached to the connecting-bar G in any convenient and well-known manner.

It will be understood that the different rollers are all to travel in the same direction, and by changing the pitch of the spiral tubes that each set of rollers will have a tendency to move the earth in opposite directions, thereby providing a better means for pulverizing, and 70 at the same time the rollers will be cleaned by reason of the inner sides of faces of the rollers coming in close contact with each other; but it will be understood that the rollers should be spaced far enough apart to provide 75 room for the spiral tubes to rotate with the rollers without coming in contact with each other.

Having fully described my invention, what 80 I claim as new, and desire to secure by Letters 85 Patent, is—

In a land roller, the combination of the rollers C and D, located one set in front of the other, and properly journaled, the peripheries of said rollers provided with ribs or tubes located spirally upon said rollers, and of opposite pitch, substantially as and for the purpose set forth. 90

In testimony that I claim the above I have hereunto subscribed my name in the presence 95 of two witnesses.

IRA E. STUMP.
